Patented Dec. 16, 1924.

UNITED STATES PATENT OFFICE.

EMIL DIETZE, OF NEW YORK, N. Y., ASSIGNOR TO AMERICAN CASTING AND MANUFACTURING CORPORATION, OF BROOKLYN, NEW YORK, A CORPORATION OF NEW YORK.

CAR SEAL.

Application filed July 12, 1922. Serial No. 574,491.

To all whom it may concern:

Be it known that I, EMIL DIETZE, a citizen of the United States, and resident of the borough of Queens, in the county of 5 Queens, city and State of New York, have invented certain new and useful Improvements in Car Seals, of which the following is a specification, reference being had therein to the accompanying drawing.

10 My present invention relates to certain new and useful improvements in car seals for securing the contents of freight cars and for other purposes; one object among many that might be mentioned being to simplify 15 and perfect devices of this kind so that their manufacture may be less expensive and the locking effect produced by the inter-engagement of the parts may be very secure and strong, so as to effectually prevent any 20 disengagement, or any unauthorized tampering with the parts.

The class of seals with which I am primarily concerned employs a shackle of frangible material or sheet-metal, as tin, that 25 is bent upon itself and carries a hollow head, bulb or housing into which both ends 30 of the shackle are inserted and held against withdrawal by automatic locking means within the head.

35 The invention may be said therefore to consist essentially in the construction, arrangement and combination of parts, substantially as will be hereinafter described and claimed.

In the annexed drawing illustrating my invention:

Figure 1 is a perspective view of my improved car seal, in its operative position with the shackle locked in the bulb or head, 40 both the permanent and loose ends of the shackle being locked.

Figure 2 is an enlarged sectional plan view of certain of the parts on the line 2, 2, of Figure 3.

45 Figure 3 is a vertical sectional view of the head or bulb and both the ends of the shackle locked within the same, the section being taken in a plane at right angles to the section of Figure 2.

50 Figure 4 is a cross-section on the line 4, 4, of Figure 3.

Figure 5 is a vertical section similar to Figure 3, but with the ends of the shackle shown outside of the head before they are

55 inserted into the latter for locking inter-engagement.

Figure 6 is a perspective detail view of one form of spring-catch or lock.

Figure 7 is a detail perspective view of 60 one end of the shackle.

Figure 8 is a detail perspective view of the other end of the shackle.

Figure 9 is a plan view of a blank cut out 65 of sheet metal before it is bent into shape to form the channel piece.

Figure 10 is a sectional view of the bulb or head, similar to the section in Figure 5, and shows an alternative form of spring-catch or lock arranged therein.

Figure 11 is a detail perspective view of 70 the same alternative form of catch.

Similar characters of reference designate like parts throughout all the different figures of the drawing.

75 There are four main mechanical members in my seal device, namely, the shackle, the channel piece, the spring catch or lock, and the head or bulb. The ends of the shackle are introduced into the channel piece, which is located within the bulb, and the spring 80 catch also in the bulb locks these shackle ends in said channel-piece, one end of the shackle being permanently attached when the parts are originally assembled, and the other left loose for insertion when the seal 85 is operatively applied for use.

1 denotes the shackle, which is of suitable material, as sheet-metal, tin for example, and easily breakable when desired, though when once broken it cannot be restored or 90 reattached to the other parts. In applying my improved seal to a car or otherwise the two ends of the shackle 1 are bent around so as to be opposite each other, and are both inserted into the bulb or head 2, as shown 95 in Figure 1.

One end of the tin strap or shackle 1, as 95, is shown in Figure 7, and is provided with one or more parallel slots 17 and 18, near the end thereof, said end being indented at 14 between the prongs 13, 13. Near the indent 14 is a tip or lug 15, preferably stamped out, and having a locking function with the channel piece, as I shall 100 presently explain; and near the innermost slot 17 is a lug or projection 16, also preferably stamped out of the metal, and acting as a stop to prevent the shackle end 9 from

being pushed too far into the channel piece. The prongs 13, 13, may be omitted when desired, provided the end of the shackle which forms the bottom edge of the notch 14 is the right distance from the stop 16 to bring said notch or end 14 in the proper place relatively to the channel piece. Further this end *a* of the shackle is preferably transversely curved, as shown in Figure 7, in order to make it fit more tightly in the flat throat or channel of the channel piece. It may carry any kind of an inscription, as for example, the name or initials of the railroad company, as "P. R. R." The shackle end *a* is permanently attached in assembling the parts.

The other end of the shackle 1, as *b*, is shown in Figure 8, and is similarly provided with one or more parallel slots 20 and 21 of the same size and shape as slots 17 and 18, and adapted to coincide with the latter when the two ends *a* and *b* are in place in the head 2, as seen in Figure 3. The end *b* is provided near the innermost slot 20 with a lug or projection 19, preferably stamped out of the metal, and acting as a stop to prevent the shackle end *b* from being pushed too far into the channel piece, while the end 22 of the part *b* is squared across or otherwise shaped, so that the length of part *b* from the stop 19 to the end 22 will be longer than the length of part *a* from the stop 16 to the bottom edge of notch 14, in order that the end 22 may function with the spring lock, as I shall explain. The part *b* may also carry any suitable inscription, as a number, for example "3595." End *b* of the shackle is loose until the seal is in use; then it will be locked in the head.

The bulb or housing 2 is made in a single integral piece, like a cap or thimble, with a flange 3 around its open end, which flange is caused to fit tightly over the circular edge of the bottom plates 4 of the channel piece. The mode of connecting the parts 2 and 4 together may vary greatly, but if the edge of the bulb 2 is grooved and flanged so that it can be bent over members 4 as shown, it will securely hold the said plate members 4 of the channel piece so that there will be a very firm union of these parts; and no means of entrance into the bulb after these parts are united can be had except through the slot 29 found at the bottom of said channel piece and admitting to the channel 30, as shown in Figure 5, which channel 30 runs axially into the bulb 2 and is supported therein and effectually protected thereby.

This channel or channel piece, as I term it, is preferably formed by first cutting out a sheet metal blank, an example of which is shown in Figure 9 and then bending said blank into the channeled shape shown in Figures 2, 3 and 5. This blank has the two main duplicate sections A and

B, divided by the dotted line 12, 12, each of these sections consisting of a semicircular end portion 4, situated at the end of a straight section 5, that merges into a curved-edged section 6, at the end of which is the dividing line 12, 12, contiguous to which dividing line on two adjacent spaced parallel lines of bending within the ends of the recess 7, the said two sections A and B are bent at right angles, as clearly shown in Figure 5, so as to lie alongside of and parallel to each other, while the semicircular parts 4, 4, are bent at right angles to the sections 5, 5, and together form the circular base of the channel piece, which base is connected to the end 3 of bulb 2, as already explained. One section 5 is somewhat narrower than the other section 5, the narrow one having right-angled side flanges 10, and the wider one having right-angled side flanges 11 that are larger than and adapted to overlap the flanges 10 when the sections 5, 5, are folded alongside of each other to form the channel 30 as seen in Figure 5, and said flanges 10 keep the parts 5, 5, separated from contact with each other so as to leave the channel 30 free and clear for the entrance of the shackle ends *a* and *b*, and preserve an open throat or channel which cannot collapse or be pressed together or obstructed at any time, as these flanges positively hold the members 5 at the proper distance from each other. See Figure 4 and also Figures 3 and 5 which indicate the flat channel 30 in the channel piece, and the entrance 29 thereto. The sections 5, 5, are provided with inner slots 8 and outer slots 9, the two slots 8 coinciding with each other after the blank is folded, and the two slots 9 coinciding with each other after the blank is folded. Said blank has also a central cut out opening 7 in both sections 6, 6, that furnishes the space in which the tip ends of the members *a* and *b* and the spring catch function when they are interlocked with the channel piece. This recess has the bottom edges *c*, *c*, as seen in Figures 2 and 9, over which the lip 15 engages, while the members 6, 6, form holders between them at each side of the space 7 for the prongs 13 on the shackle, that is to say the laps form a slide so that the shackle ends must slide between them in a direct passage, provided said prongs are used, though they may be dispensed with as suggested.

It will thus be seen that the two ends of the shackle 1 can be inserted into the channel piece alongside of each other, as shown in Figures 3 and 5. In Figure 5 the two ends are shown outside the bulb and in readiness to be inserted. In Figure 3 they are shown as inserted and locked therein. The end *a* will be inserted first, for this is a permanent attachment made in assem-

bling the parts, and will be pushed in through mouth 29 and throat 30 until the lug 15 engages the edge *c* in the bottom of cut-out recess 7 and the stop 16 will abut against the bottom 4 of the channel piece and keep the shackle end *a* from going in any further. Then when the seal is used the end *b* will be inserted alongside of end *a* until its stop 19 abuts against the bottom 4 of channel piece and prevents end *b* from a further advance, at which time the end 22 of the part *b* will be beyond the lug 15, as shown in Figure 3, in order to actuate the spring latch or lock, as I shall explain. With this construction therefore it is impossible to insert anything into the channel piece except the two ends of the shackle; the channel piece is so made that it cannot be spread open to allow anything else to enter thereinto; and if the shackle is broken the broken end cannot be re-inserted into the channel, for the broken piece will be inside, locked securely against withdrawal, and hence the throat 30 will be full and nothing else can enter; thus the security of the seal against tampering is insured.

Thus the bulb, housing or head in one piece entirely encloses the locking mechanism and prevents tampering with the seal, as so often happens when the head is made of two or more parts. With such construction it is impossible to squeeze the bulb or channel together and make the slot smaller. This is mentioned because one method of tampering with car seals is to break off one end of the shackle after it has been locked, and re-insert it into the slot as far as it will go and squeeze the slot together to hold it, thereby making the seal appear to have not been tampered with. Hence I have this extra precaution in the provision of a structure where it is impossible to insert anything but the two ends of the shackle.

Having described three of the chief elements of my seal, the fourth important fundamental feature of the seal is the interior free locking spring or spring catch that automatically engages the inner ends of the shackle within the bulb and locks them within the channel piece. This catch may be made in many forms. I show two alternative forms, one of which, as 23, is indicated in Figures 2-6; and the other, as 31, is shown in Figures 10 and 11. While differing in detail, they have common essentials, and obviously function in the same manner, while moreover, there is a wide latitude in the shapes they may take and the additional ways in which they may be modified and related. The first form 23 is bent into a U-shape to provide two parallel spring plates 27 and 28, said plate 27 having a lip 24 at right angles thereto and projecting toward plate 28, and

plate 28 having two similar lips 25 and 26 (though it may have only one, or as many as desired), projecting toward plate 27. This U-shaped device normally embraces the channel piece, and being of spring metal 70 clasps the two flat sides of the latter very firmly, as shown in Figure 5, with the lip 24 projecting into the slot 7 between parts 6 and against or a short distance from lower edge *c* of slot 7, and with the lip 25 resting 75 tight against the side of channel piece adjacent to slots 8 and the lip 26 also tight against side of channel piece adjacent to slots 9. This will be the position of the spring lock when the parts are assembled 80 and before the ends of the shackle are inserted into the channel and also after end *a* has been inserted; and in order to properly position said lock its bottom edge may at this time rest against some part, or its lip 24 85 may rest against edge *c*, in order that the lock may not be displaced before exerting its locking action on the shackle. In the other form of lock which I have shown 90 31 denotes an oblong spring metal element, having two opposite sides 33 and 37 connected by a bend 32, said device embracing the channel piece, with the bend 32 lying normally in the end recess 7 against the bottom edge *c* thereof, and with side 37 pressing 95 against one of the flat sides 5 of the channel, and the other side 33 having a cut-out at 36 to form a lip 35 that tightly engages the opposite side 5 of the channel near slots 8 and another lip 34 that tightly engages the same side 5 adjacent to the slots 9, while the side 37 is preferably curved to provide wing edges 38 that slide between overlapping flanges 11 of the channel so as to guide and center the lock in its movement to locking 100 position. Thus in this form 31 the bend 32 is equivalent in function to the lip 24 of form 23, and the lips 34 and 35 to the lips 105 25 and 26.

In the interlocking of the parts within the bulb the operation of the spring catch is in both cases precisely the same. I have shown that the channel piece has two sets of slots, as 8 and 9, with which the twin lips or lugs on the catch device snap and engage 110 when the device is moved toward the end of the channel from the normal position above described. One of these locking points is therefore directly at the entrance to the channel, so the shackle locks there and obstructs the passage and eliminates pilfering, and the other is placed well within the bulb. Of course one locking point will be measurably effective, but I may have several if desired, the number being variable, and therefore the lock may have single or double locking lips.

Now the shackle ends *a* and *b* are inserted into the central passage 30 in the channel piece. First the end *a* is inserted and per-

- manently engaged. Its transversely curved form causes it to bind against the walls 5 of channel 30 and make a tight fit as it is being inserted, and when clear in and stop 5 16 has hit bottom 4 the lug 15 will snap over edge *c* in slot 7, but the end of part *a* is not long enough to strike and disturb the spring catch or locking spring, for the prongs 13, if used, will be on opposite sides of the 10 lip 24. When the loose end *b* of the shackle is inserted into the head, the end 22 of same will come into contact with lip 24 of the spring catch and by pushing it ahead will move the catch and cause the lugs or prongs 15 25 and 26 to snap into slots 8 and 9, as well as into slots 17 and 18 and 20 and 21 of the shackle, which slots are now registering with slots 8 and 9, see Figure 3, so that both ends of the shackle are locked to the channel 20 piece. The spring catch may be made of any resilient material, and may be round or flat or any shape. A similar action takes place when spring catch 31 is used instead of spring catch 23. Further, not only does a 25 double locking spring hold the parts together more strongly, but the spring catch absolutely blocks off any entrance into slot 29 of the seal with any small tool or appliance with the idea of picking the catch. If 30 it were possible to break the catch at the first prong, the second locking prong would still be intact and beyond reach.

Thus I provide a very strong seal. The construction of the shackle in combination 35 with the channel piece is such that the manufacture of the seal is greatly simplified, in that the bulb with the entire locking means can be made separately and ahead of time, which includes most of the operations on 40 such seal. The shackles then are stamped out and numbered and lettered as you please. It is then only necessary to insert the end of the shackle that is to be permanent into the bulb where it locks. Obviously many 45 changes in detail and precise construction may be made at times for convenience.

Having thus described my invention, what I claim as new and desire to secure by Letters Patent, is:

- 50 1. In a seal, the combination with a bulb or head, of a channel member consisting of parallel slotted pieces, supported rigidly within the bulb, a shackle whose ends are adapted to be inserted in the channel member, one end having a lug and engaging the channel member, and a spring catch within the bulb for interlocking both ends of the shackle and the channel member.
- 60 2. In a seal, the combination with a bulb or head of a channel member, consisting of parallel slotted pieces supported rigidly within the bulb, a shackle having ends of different length which are adapted to be inserted separately into the channel member, and a locking spring within the bulb, em-

bracing the channel member, which spring is automatically acted upon by the insertion of the longer end of the shackle, for the purpose of interlocking both ends of the shackle and the channel member.

3. In a seal, the combination with a bulb or head of a channel member within the bulb, a shackle with ends of different length adapted to be inserted separately into the channel member, one end having a lug and 70 engaging with the channel member, and a locking spring within the bulb, clasping the channel member and operating the interlocking ends of the shackle and the channel member, said interlocking automatically taking place when the longer end of the shackle actuates the spring.

4. In a seal, the combination with a bulb or head, of a channel member, consisting of parallel slotted pieces, supported rigidly 85 within the bulb and a spring catch and a shackle with ends of different length, adapted to be inserted into the channel member, one end having projecting means to interengage with the channel member, without affecting the spring catch, and the other long end of the shackle automatically causing the spring catch to operate and engage the slots in the channel member.

5. In a seal, the combination with a bulb or head, of a channel member within the bulb, a shackle having end portions provided with slots and stop means for limiting their inward movement into the channel member, one having a lug engaging the channel member, and a spring catch within the bulb that is caused to act when moved by the other end of the shackle.

6. In a seal, the combination with a bulb or head, of a channel member, within the bulb, a shackle having end portions of different length that are adapted to be inserted into the channel member separately, one end portion having a projection to engage the channel member, together with a spring catch within the bulb, clasping the channel member, for engaging said end portions of the shackle separately and locking them together and to the channel member.

7. In a seal, the combination with a bulb or head, of a channel member, consisting of parallel slotted pieces, having angular plates held rigidly within the bulb, a shackle having end portions of different length that are adapted to be inserted separately into the channel member within the bulb and means for separately securing said end portions within the channel member, consisting of a lug on one end portion and a spring catch, which operates to lock the members together when said catch is actuated by the insertion of the longer end of the shackle.

8. In a seal, the combination with a bulb or head, of a channel member secured therein and having a central throat or passage 130

- formed by slotted parallel integral side pieces, a shackle having end portions of different length adapted to be inserted into the channel member, means for locking one of the ends of the shackle when so inserted, and other means consisting of a spring catch actuated by the other end of the shackle when inserted, for interlocking both ends of the shackle and the channel member
- 10 together.
9. In a seal, the combination with a bulb or head, of a channel member within the bulb, having a throat formed by parallel integral slotted pieces having angular plates secured rigidly within the bulb, a shackle whose ends enter the throat of the channel member and are provided with openings to register with the openings in said channel member, and a spring catch that embraces the channel member and has prongs or lips to engage the said openings therein and in the shackle ends when the spring catch is set free by contact with the actuating end of the shackle.
- 15 10. In a seal, the combination with a one-piece thimble housing, of a channel member secured in the open end thereof, and having a central passage serving as a throat and formed between two parallel slotted integral side pieces, said channel member projecting into the housing, and a shackle whose ends are inserted into the passage in the channel member, together with a spring catch clasping the channel member, and restrained from exercising its locking effect on the parts until the end of the shackle is inserted having the function of moving the catch.
- 20 11. In a seal, the combination with a thimble housing, of a channel member having a slotted base secured to the open end of the thimble and with a central passage in communication with the slotted base, the
- 25 shackle having slotted ends that are insertible into the channel member, and a spring catch within the housing having prongs to engage the shackle ends and the channel member.
- 30 12. In a seal, the combination with a bulb or head, of a channel member having a slotted base and a central passage in communication with the slotted base, said channel member being supported rigidly within the bulb, a shackle having ends of different length insertible into the channel member, and a spring catch within the bulb clasping the channel member and normally restrained from locking until set free by the longer end of the shackle.
- 35 13. In a seal, the combination with a bulb or head, of a channel member secured to the open end of said bulb and projecting into the bulb, the said channel member having a central opening and a passage formed by overlapping flanges to provide a non-compressible holder for the shackle, a shackle having ends of different length and insertible into the channel member, and a spring catch within the bulb clasping the channel with a spring action and normally restrained from locking until set free by contact with one end of the shackle.
- 40 14. In a seal, the combination of a bulb or head, a channel member consisting of parallel slotted pieces supported rigidly within the bulb, a shackle having its ends inserted into the channel member, and a spring clasp consisting of a twin-sided member embracing the channel member and adapted to be actuated by one end of the shackle, said spring clasp having prongs or lips which engage slots in the channel member and the ends of the shackle.

In testimony whereof I hereunto affix my signature.

EMIL DIETZE.
